(57) **CLAIM**

The ornamental design for a stuffed animal, as shown and described.

DESCRIPTION

FIG. 1 is a front, left, top perspective view of my new design for a stuffed animal;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The stitching indicated in broken lines in the drawings represents environmental subject matter and forms no part of the claimed design. The dashed broken lines showing the eye lashes is for environmental purposes only and forms no part of the claimed design.
